UNITED STATES PATENT OFFICE

ROBERT F. BRIMER, OF WASHINGTON, DISTRICT OF COLUMBIA, ASSIGNOR OF ONE-HALF TO WALTER B. AVERY, OF WASHINGTON, DISTRICT OF COLUMBIA

COMBINED WRAPPER OR ENVELOPE AND GUARD FOR FROZEN CONFECTIONS

Application filed May 26, 1927, Serial No. 194,354. Renewed April 22, 1930.

This invention relates to combined wrappers or envelopes and guards for frozen confections, and it comprises a container such as a water-proofed or glazed paper envelope 5 adapted to receive the confection and a stiffening member such as a reinforced sheet of heavy paper or pasteboard or thin metal or the like attached, preferably by means of adhesive, to one surface of the container, such 10 reinforcing member being perforated by a hole advantageously somewhat smaller in diameter than the stick or handle carrying the confection and the other surface of the envelope being, advantageously, provided 15 with an indicating mark registering with the said perforation, whereby when the confection is removed from the envelope the handle may be forced through one surface of the envelope at the indicated point and through 20 the perforation of the reinforcement, to a point where the envelope acts as a shield or guard, preventing drippings from the confection contaminating the handle or the hand or clothes of the consumer; all as more fully 25 hereinafter set forth and as claimed.

Certain confections such as frozen confections or other delicacies such as candies and pastries are provided with sticks or handles which the person may hold while consuming them. These confections are usually sold in water-proofed envelopes which the user throws away when he is about to consume the confection. It is an object of my 30 invention to so construct the envelope or container that it may be used as a shield or guard to protect the consumer from the drippings of the confection as it is being eaten. This object I accomplish by providing one side of the envelope with a relatively stiff reinforcing 35 member preferably scored or creased somewhat in one direction and by providing the other surface of the envelope with an indicating mark registering with the perforation of the reinforcing member.

40 When the purchaser decides to eat the confection he removes it from the envelope and forces the end of the handle or stick through the indicating mark on the one surface of the envelope, through the other surface of the 45 envelope and then through the perforation of

the reinforcing member. The force necessary to penetrate the paper of the envelope and the perforation in the reinforcing member will be sufficient to bend the reinforcing member somewhat along the scored or weakened portion and therefore dish it so that there is provided directly under the confection a dish-like receptacle formed by the perforated reinforcing member and the material of the envelope. The perforation in the reinforcing member may be somewhat smaller than the diameter of the stick or handle and if desired the end of the stick or handle may be pointed to facilitate penetration of the paper of the envelope. In some instances 55 instead of using a reinforcing member of cardboard, thin metal or the like I may use several plies of such material and preferably several plies of paper which may be of the same composition and character as that of the 60 envelope.

In the accompanying drawing I have shown several forms of a specific embodiment of my invention.

In the drawings:

Fig. 1 is a perspective showing a transparent envelope with the confection therein as usually dispensed.

Fig. 2 is a perspective showing the handle of the confection forced through the reinforcement and illustrates the dishing of the container and the position of the confection for consumption.

Fig. 3 is a top plan view of the envelope showing the reinforcement on the reverse side in dotted lines.

Fig. 4 is an enlarged section on line 4—4 of Fig. 3 with the reinforcement spaced away slightly for clarity of illustration.

Fig. 5 is a transverse section through the envelope and reinforcement and illustrates a modified form of the invention.

Figs. 6, 7 and 8 illustrate several modifications of reinforcing members which may be used.

Referring to the drawings, 1 indicates as a whole a transparent envelope having the front side 2 and the rear side 3. This may be made in any way, usually by simply pasting the ends 4 and 5 together and by turning 100

over the end 6, thus leaving an opening preferably with a flap 7. As so far described, this is the usual construction. In addition to this construction, in accordance with my invention, I provide a reinforcing member 8 which may be of relatively heavy paper, cardboard (pasteboard), thin flexible metal, celluloid, or other material relatively stiff as compared to the material of which the envelope itself is made. This reinforcement 5 may consist of a heavy layer of celluloid or glue-like substance. The reinforcing member 8 is preferably secured to the under side of the envelope by means of a suitable adhesive and is provided, preferably, at about its mid-point, with a perforation 9, advantageously, somewhat smaller than the diameter of the handle A which carries the confection so that when the handle is forced through this 10 perforation, as hereinafter described, the fit will be a tight one and there will be some resistance to the passage of the handle through the perforation, resulting in a tendency to cup or dish the sides of the reinforcing member upwardly. On the front of the envelope I place a suitable indicating or index mark by means of color or otherwise illustrated in Fig. 3 and designated by reference numeral 10. This indicating mark should 15 register with the perforation of the reinforcing member so that when the user forces the handle of the confection through this indicating mark it will perforate the upper side of the envelope, then perforate or pierce the 20 under side of the envelope and then register with the hole in the reinforcing member. The envelope itself is preferably not perforated as it is better that it should be a water-proofed and sealed package for sanitary 25 purposes. The reinforcing member 8 is better placed on the under side of the envelope and I prefer to arrange it in such a way so that the perforation or hole 9 of the reinforcing member is directly under the 30 overlapping flaps 4 and 5. These flaps offer a little resistance to the passage of the handle through the paper and thus serve to help "cup" the container.

In Fig. 5 I have illustrated a somewhat 35 modified form of the invention in which a plurality of reinforcing members are used instead of one. These reinforcing members are positioned under the flaps 4 and 5 and any number of them may be used. For sake 40 of illustration I have shown the reinforcing member 8 of the same construction as the ones previously and hereinafter described and the intermediate one or ones 11 may be of the same material or of thin paper or the like. And since I may use several of these it is sufficient in some instances that they merely be 45 of paper of the same character as that of which the envelope itself is made. In other words, I may construct a reinforcing member of paper similar to that of which the envelope

is made and use a sufficient number of plies of such paper to afford the necessary stiffness. In Figs. 6, 7 and 8 I have shown several modified forms of reinforcing member 8. In Fig. 6 this may be an ordinary square and positioned with opposite corners in line with the longitudinal line of the envelope. In Fig. 7 50 I have shown the reinforcing member 8 of rectangular shape extending substantially the entire length of the envelope; and in Fig. 8 55 I have shown the reinforcing member 8 in the shape of a circle. In order to facilitate the cupping or dishing of the reinforcing member I preferably weaken it along one line. This may be done by scoring it or in any ordinary way of weakening materials of the character of those which may be used. The scoring is indicated in Figs. 1, 6, 7 and 8 by reference numeral 12.

The manner of use of this device is obvious 60 from the foregoing. When the purchaser decides to consume the confection he removes it from the envelope, flattens the envelope in one hand and while holding the envelope with one hand forces the handle of the confection through the upper face of the envelope at the point indicated by reference numeral 10 if such indicia are used. In doing this the fingers holding the envelope on the under side should be spaced somewhat apart 65 in order that the handle may pass through the under side of the envelope and into the perforation 9 of the reinforcing member. With the fingers held somewhat apart and on the opposite sides of the scored portions 12 70 and with force sufficient to cause the handle to penetrate the paper there will be a tendency for the envelope to assume a concave shape and this shape will be retained because the scored portion of the reinforcing member 75 having weakened it to a limited extent prevents that reinforcing member from springing back or resuming its normal flat position. If the envelope should be made of particularly stiff or heavy paper or other material, 80 rather than perforating it for the purpose of permitting the handle to be properly positioned I may sharpen the extreme end of the handle and thus provide a point for penetrating the paper, but ordinarily this is not 85 necessary since, I wish to use the resistance of the paper to the passage of the handle therethrough to aid in dishing or cupping the reinforcing member and thus the envelope. The envelope is best made of glazed or 90 paraffined or otherwise water-proofed paper, but for economy in manufacture the reinforcing member need not necessarily be of such material.

What I claim is:—

1. A combined envelope and guard for confections provided with handles, comprising a container adapted to receive the confection, and a reinforcement provided with a weakened spot on one surface of the container,

whereby the handle of the confection may be forced through two sides of the container and through the weakened spot of the reinforcement to position the container under the confection and on the handle.

5 2. A combined envelope and guard for confections provided with handles, comprising a container adapted to receive the confection, and a perforated reinforcement on one surface of the container, whereby the handle of the confection may be forced through two sides of the container and through the reinforcement to position the container under the confection and on the handle.

10 15 3. A combined envelope and guard for confections provided with handles, comprising a container adapted to receive the confection, a reinforcement on one surface of the container, a weakened spot in said reinforcement and an indicating mark on the opposite surface of the container, said indicating mark registering with said weakened spot in said reinforcement, whereby the handle of the confection may be forced through two sides 20 25 of the container and through the reinforcement to position the container under the confection and on the handle.

4. A combined envelope and guard for confections which are provided with handles, comprising a container adapted to receive the confection and a relatively stiff reinforcing member on one side of the container, said member being weakened along its length, whereby the handle may be forced through 30 35 the container and the member and tend to bend the member along the reinforcement to make a dish-like receptacle.

5. A combined envelope and guard for frozen confections comprising a container 40 adapted to receive the confection formed of waxed paper in the shape of a bag, a perforated reinforcing strip disposed along the back of the container, said reinforcement strip having a scoring along its length passing 45 through said perforation, and an index spot positioned on the opposite surface of the container in registration with said perforation.

6. A combined envelope and guard for frozen confections comprising a container 50 adapted to receive the confection formed of waterproof flexible material in the shape of a bag, a reinforcing member positioned on one surface of the bag and having a perforation of small diameter formed therein, and 55 an index spot positioned on the opposite surface of the bag.

In testimony whereof, I have hereunto affixed my signature.

ROBERT F. BRIMER.
